US0D1052689S

(12) **United States Design Patent** (10) Patent No.: **US D1,052,689 S**
(45) Date of Patent: ** Nov. 26, 2024

(54) **NOZZLE**

(71) Applicant: **Altair (UK) Limited ("Parker")**,
Hemel Hempstead (GB)

(72) Inventors: **Kate Taylor**, Liphook (GB); **Alastair Lee**, Fleet (GB)

(73) Assignee: **Altair (UK) Limited ("Parker")**,
Hemel Hempstead (GB)

(**) Term: **15 Years**

(21) Appl. No.: **29/848,986**

(22) Filed: **Aug. 8, 2022**

(51) LOC (14) Cl. **23-01**

(52) U.S. Cl.

USPC **D23/213**

(58) **Field of Classification Search**

Primary Examiner — Keith J Wilson

(57) **CLAIM**

The ornamental design for a nozzle, as shown and described.

DESCRIPTION

FIG. 1 is a perspective view of a nozzle showing our design; FIG. 2 is a front elevation view of the nozzle of FIG. 1; FIG. 3 is a rear elevation view of the nozzle of FIG. 1; FIG. 4 is a right-side elevation view of the nozzle of FIG. 1, the left side being identical; FIG. 5 is a top plan view of the nozzle of FIG. 1; and, FIG. 6 is a bottom plan view of the nozzle of FIG. 1. The broken lines shown herein are for illustrative purposes only and form no part of the claimed design.

1 Claim, 6 Drawing Sheets
